Attorney, Agent, or Firm—Lothrop & West

[57] CLAIM

The ornamental design for a rotatable tie rack, as shown and described.

DESCRIPTION

FIG. 1 is a top plan view of a rotatable tie rack, showing my new design;

FIG. 2 is a side elevational view taken on the plane indicated by the lines 2—2 in FIG. 1;

FIG. 3 is a bottom plan view;

FIG. 4 is a side elevational view taken on the plane indicated by the lines 4—4 in FIG. 1;

FIG. 5 is an enlarged side elevational view of the closet rod clamp bracket and saddle depending therefrom, shown separately for clarity of illustration;

FIG. 6 is an enlarged end elevational view of FIG. 5.
